GAS STOVE

Filed May 2, 1927

2 Sheets-Sheet 2

UNITED STATES PATENT OFFICE.

HUBERT R. HUMPHREY, OF KALAMAZOO, MICHIGAN, ASSIGNEE TO GENERAL GAS LIGHT COMPANY, OF KALAMAZOO, MICHIGAN.

GAS STOVE.

Original application filed November 6, 1925, Serial No. 67,277. Divided and this application filed May 2, 1927. Serial No. 188,195.

The structure of this application is especially designed by me for embodiment in cooking stoves such as illustrated in my application for Letters Patent filed November 6, 1925, Serial No. 67,277, of which application this is a division. My improvements are, however, readily embodied and desirable for use in heating stoves.

The main objects of this invention are to provide an improved gas stove of the radiating element type which is well adapted for structures of considerable size and at the same time is strong and rigid.

Objects relating to details and economies of construction and operation of my invention will appear from the detailed description to follow.

The invention is defined and pointed out in the claims.

A structure which is a preferred embodiment of my invention is illustrated in the accompanying drawing, forming a part of this application, in which:

Fig. 1 is a front perspective view of a structure embodying the features of my invention.

Fig. 2 is a vertical section on line 2—2 of Fig. 1.

Fig. 3 is a front perspective view of the skeleton or main supporting portions of the frame.

Fig. 4 is a fragmentary section on line 4—4 of Fig. 2.

Fig. 5 is a fragmentary front elevation with the hearth plate removed.

In the drawings similar numerals of reference refer to similar parts throughout the several views.

Referring to the drawings, the supporting part of the skeleton or body of my improved stove comprises a pair of end members 1, 1 which are preferably castings and have extended base portions 2 terminating in feet 3 and forwardly projecting overhanging top portions 4. The end members are supported in spaced relation by means of the tie rods 26, 27 and 28.

The end members are provided with a plurality of inwardly projecting lugs 5 adapted to receive the bolts 6, securing the back frame 7 thereto. This back frame has a panel 8 secured thereto by means of the screws 9. The back frame has forwardly projecting lugs 10

supporting the rear end of the hood-like top 11, this top having a downwardly projecting rib 12 adjacent its rear edge resting on the lugs, as shown in Fig. 2.

The top has down-turned flanges 13 at its ends embracing the upper edges of the end members. At its front end, the top is provided with inturned ears 14 engaged by the screws 15 through the end members.

The rear panel 8 has an opening 16 therein to receive the flue collar 17.

A rear bottom panel 18 extends between the rearwardly projecting ends of the base portion and is secured by means of screws 19, engaging ears 20 on the end members, and by means of the ears 21 on the panel engaged by the screws 22.

The front base panel 23 is provided with inturned ears 24 secured to the end members by the screws 25.

The supporting plate 29 is mounted on the end members by means of lugs 30 and is further supported by screws 31 engaging the downwardly projecting flange 32 on the rear of the plate, the screws being arranged through the back frame 7. This supporting plate 29 has a downwardly projecting flange 33 at its front edge on which the burner 34 is mounted. The plate has holes 35 therein above the tips of the burner.

The fireback 36 is mounted on this plate 29 and in front of this, the radiating elements 37 are arranged in operative relation to the burner tips. A retaining bar 38 engages the top of the fireback and has forwardly projecting arms 39 which are secured to the end members 1.

The radiating elements are retained on the plate 29 by means of the retaining rod 40 which has downwardly offset loops 41 at its ends engaged by the screws 42, these screws having a bar-like head, as shown in Fig. 5.

The fireback is further retained by means of the lugs 43 and 44 projecting inwardly from the frame end members 1 to engage the front edges of the fireback.

Finishing or corner plates 45 are secured by means of the screws 46 to the front flange of the supporting plate to overlap the lower end of the fireback adjacent the end members.

The hearth plate 47 is mounted in front of the supporting plate, the end members being

provided with notched lugs 48 with which the lower edge of the hearth plate is engaged, the upper edge of the hearth plate resting against the corner plates 45. The hearth plate 47 is spaced from the front panel 23 providing an opening between the forwardly projecting arms of the end member base portions to receive a pan 49, the pan resting upon the ledges 50 on the end members. This pan is especially provided for use when the structure is adapted as a cooking stove.

I have illustrated and described my improvements in an embodiment which I have found very practical for stoves of considerable size. I have not attempted to illustrate or describe my improvements in other adaptations and embodiments which I contemplate as it is believed the disclosure made will enable those skilled in the art to embody or 20 adapt my improvements as may be desired.

Having thus described my invention, what I claim as new and desire to secure by Letters Patent, is:

1. In a gas stove, the combination of a frame comprising upright end members and tie rods connecting said end members in spaced relation, said end members having inwardly projecting lugs at the rear edges thereof, a back secured to said lugs on said end members, a top mounted on said end members, a supporting plate mounted on said end members, a burner mounted below said supporting plate, a fireback disposed on said supporting plate, radiating elements mounted on said supporting plate in operative relation to said burner, and a hearth plate mounted on said end members in front of said supporting plate, said end members being provided with supporting lugs for said hearth plate.

2. In a gas stove, the combination of a frame comprising upright end members and tie rods connecting said end members in spaced relation, a back secured to said end members, a top mounted on said end members, a supporting plate mounted on said end members, a burner suspended from said supporting plate, a fireback disposed on said supporting plate, said end members having inwardly projecting lugs engaging said fireback, and radiating elements mounted on said supporting plate in operative relation to said burner.

3. In a gas stove, the combination of a frame comprising upright end members, tie rods connecting said end members in spaced relation, a front panel mounted on said end members at the lower ends thereof, a supporting plate mounted on said end members, a burner mounted below said supporting plate, a fireback disposed on said supporting plate, radiating elements mounted on said supporting plate in operative relation to said burner, and a hearth plate mounted on said end members in front of said supporting

plate and in spaced relation to said front panel providing an opening between them to receive a pan, said end members being provided with supporting lugs for said hearth plate and with pan supporting ledges.

4. In a gas stove, the combination of a frame comprising upright end members and tie rods connecting said end members in spaced relation, a front panel mounted at the lower ends of said end members, a supporting plate mounted on said end members, a burner mounted below said supporting plate, a fireback disposed on said supporting plate, radiating elements mounted on said supporting plate in operative relation to said burner, and a hearth plate mounted on said end members in front of said supporting plate and in spaced relation to said front panel providing an opening adapted to receive a pan, said end members being provided with supporting ledges for said pan.

5. In a gas stove, the combination of a frame comprising upright end members, tie rods connecting said end members in spaced relation, a supporting plate mounted on said end members, a burner mounted below said supporting plate, a fireback disposed on said supporting plate, and radiating elements mounted on said supporting plate in operative relation to said burner.

6. In a gas stove, the combination of a frame comprising upright end members and tie rods connecting said end members in spaced relation, a back secured to said end members, a top mounted on said end members, a supporting plate mounted on said end members, a burner suspended from said supporting plate, a fireback disposed on said supporting plate, and radiating elements mounted on said supporting plate in operative relation to said burner.

7. In a gas stove, the combination of a frame comprising upright end members and tie rods connecting said end members in spaced relation, a supporting plate mounted on said end members, a burner suspended from said supporting plate, a fireback disposed on said supporting plate, said end members having inwardly projecting lugs engaging said fireback, and radiating elements mounted on said supporting plate in operative relation to said burner.

8. In a gas stove, the combination of a frame comprising upright end members and tie rods connecting said end members in spaced relation, a supporting plate mounted on said end members, a burner suspended from said supporting plate, a fireback disposed on said supporting plate, and radiating elements mounted on said supporting plate in operative relation to said burner.

9. In a gas stove, the combination of a casing, a supporting plate having a depending flange at its front edge mounted within said casing, a burner mounted on said flange be-

low said supporting plate, a fireback disposed upon said supporting plate, radiating elements disposed upon said supporting plate in front of said fireback and in operative relation to said burner, a retaining rod having a forwardly and downwardly offset loop therein, and a screw clamping said loop

against said flange whereby the rod is supported adjacent the supporting plate and in coacting relation to the lower ends of the radiating elements.

In witness whereof I have hereunto set my hand.

HUBERT R. HUMPHREY.
